SHAVING IMPLEMENT

Henry T. Schiff, Chicago, Ill.

Application May 4, 1940, Serial No. 333,383

1 Claim. (Cl. 30—43)

My invention relates to a shaving implement adapted for use as a dry shaver of the motor driven type.

Among the objects of my invention are to provide a shaving implement adapted to give as close a shave as desired by the user with positive clipping action and without pulling hair or causing a burning sensation; to create a shaving implement having a double head with eight shaving surfaces; to supply a shaving implement in which four of the shaving surfaces are substantially at right angles to the four other shaving surfaces and in which there are spaces between each of the shaving surfaces on the same plane; to afford a construction which will make the skin of the user taut so as to hold up the bristles on his face for the better shaving off of the same; to create a shaving implement which will because of its added surfaces give a multiple shaving action with ordinary application for greater speed and efficiency, and such other objects, advantages and capabilities as will later more fully appear and which are inherently possessed by my invention.

While I have shown in the accompanying drawing a preferred form of my invention, yet I desire it understood that the same is susceptible of modification and change without departing from the spirit of my invention.

Referring to the drawing, Fig. 1 is a top plan view of my shaving implement; Fig. 2 is a front elevational view and Fig. 3 is a side elevational view of the same; Fig. 4 is an enlarged detailed sectional view on line 4—4 of Fig. 3; Fig. 5 is a detailed view on line 5—5 of Fig. 2 with one head broken away to show the same in section; Fig. 6 is an enlarged top plan view showing the heads; Fig. 7 is a perspective view of an electric vibrator with two driving members.

The embodiment selected to illustrate my invention comprises a hollow casing 10, preferably of two parts, in which is arranged in any suitable manner a motor 11 as shown in Fig. 4 or a vibrator 50 as shown in Fig. 7, connected by lead wires 12 to an electrical source of supply.

Extending upwardly from the motor 11 or armature 51 of the vibrator 50 are a pair of spaced driving shafts 13, each shaft adapted to engage a head 15.

Each of my two heads 15 comprises an outer stationary member 16 and an inner movable member 17. The outer member 16 has a pair of oppositely disposed upwardly extending portions 18, bent at their upper ends at substantially right angles thereto and extending into

grally inwardly to form a pair of substantially flat top portions 19 connected by a U shaped or channel portion 20. A plurality of spaced and substantially parallel slits 21 are formed longitudinally across most of each of the top portions 19; said slits continuing at the outer edges of the top portions 19 to extend downwardly a short distance on each of vertical portions 18.

The inner member 17 is substantially channel shaped to fit and slidably move on the inner side of U shaped channel portion 20 of outer member 16. The outer edges 40 on each side of said inner member 17 are extended at substantially right angles and have a plurality of spaced serrations or teeth 22. A centrally disposed aperture 23 is cut in movable member 17 to receive the upper end of shaft 13.

A base member 52 has upward extensions 53 on each end adapted to fit within the rounded hollow end portions 54 of outer member 16 and to be attached thereto by pins 55. The base member 52 has a substantially central aperture 56 to permit the driving shafts 13 to pass therethrough to contact the movable member 17. On either side of said central aperture 56 are openings 57 to receive springs 28, the upper ends of which bear against the under portion of movable member 17 on either side of aperture 23.

The top of my casing 10 has a pair of substantially flat surfaces 58 separated by an upstanding spacer 59. Openings 24 are provided in surfaces 58, through which extend the spaced driving shafts 13. Each of my heads 15 rests with its base member 52 upon one of the flat surfaces 58 and with driving shaft 13 within central aperture 56. The bottoms of springs 28 rest against flat surfaces 58.

To attach each of my heads I provide a pair of oppositely disposed slots 29 within casing 10 and on opposite sides thereof. Within said slots 29 are perfectly fitted nuts 30 each having a screw threaded aperture 31. A pair of clamping members 32 adapted to fit within notches 36 on either side of casing 10 also have each a countersunk aperture 33. A bolt 38 passes through apertures 33 and 31. The clamping members 32 each have a slight inturned flange 34 and a center member 35 adapted to brace against the ends of the base member 52.

Having thus described my invention, I claim:

In a shaving implement a casing having a flat top portion with a centrally depressed recess, an upstanding non-shaving spacer with its lower portion resting within said recess and its upper portion extending above said top portion and

separating said top portion into two definitely spaced flat surfaces, a pair of shaving heads, each of said shaving heads having a flat bottom surface resting on top of one of the two spaced flat surfaces of said top portion, said shaving heads spaced by said spacer, each of said spaced flat surfaces of the top portion having a central opening therethrough, driving means in said casing having spaced driving shafts extending upwardly through said central openings in said spaced flat surfaces of the top portion to engage and operate said spaced shaving heads, each of said shaving heads having a pair of apertures on either side of said central opening, springs positioned

5 in said apertures with the tops of said springs bearing against said shaving heads, and the bottoms of said springs bearing against said flat surfaces of the top portion of said casing, said casing having notches on its upper side portions adjacent opposite ends of said top portion, a pair of spaced clamping members adapted to fit within said notches, said clamping members having means adapted to engage opposite ends of said shaving heads, and means adapted to removably attach said shaving heads through said clamping members to said casing.

10

HENRY T. SCHIFF.
